J. F. MacINDOE,
LUBRICATOR,
APPLICATION FILED MAY 10, 1918.

Patented Apr. 15, 1919.

John F. Mac. INDOE Inventor

M. Van Beesterv
His Attorney

UNITED STATES PATENT OFFICE.

JOHN FRANKLIN MACINDOE, OF PHILADELPHIA, PENNSYLVANIA.

LUBRICATOR.

1,300,751.

Specification of Letters Patent. Patented Apr. 15, 1919.

Application filed May 10, 1918. Serial No. 233,617.

To all whom it may concern:

Be it known that I, JOHN FRANKLIN MACINDOE, a citizen of the United States, residing at Falls of Schuylkill, city of Philadelphia, in the county of Philadelphia and State of Pennsylvania, have invented certain new and useful Improvements in Lubricators, of which the following is a specification.

10 My invention relates to grease cups or lubricators from which the lubricant is ejected by means of pressure applied thereto, the pressure gradually lessening as the volume of lubricant diminishes and the delivery 15 passage being controlled by a valve movable with the pressure device so as to gradually increase the area of such passage as the pressure upon the lubricant decreases and is an improvement on Letters Patent 20 No. 1,159,517 issued to me November 9, 1915.

The objects of the present invention are to provide means for limiting and adjusting the lead of the control valve; means for advancing or retarding the contact of the 25 regulating pin of the device with a spring, making it possible to begin opening the valve earlier or later as the tension of the spring or the requirements of the bearing 30 may require and means for locking the cover in position to prevent it from backing off.

With these and other objects in view this invention consists of the construction, combination and arrangement of parts as hereinafter more fully described, claimed and 35 illustrated in the accompanying drawings, wherein:

Figure 1 is a vertical sectional view of a lubricator constructed in accordance with my invention, the valve controlling the outlet being shown in an open position;

Fig. 2 is a top view of the locking device with its bearing;

Fig. 3 is a plan view of the lug on the body of the cup with the lock in an engaged 45 position;

Fig. 4 is a detail view of the regulating pin or valve control stem;

Fig. 5 is a view of the valve controlling the outlet on line 5—5 of Fig. 1, illustrating 50 the valve in a closed position.

Similar reference characters refer to similar parts throughout the drawings.

Referring to said drawings in detail the body or cup *a* of the lubricator is closed at 55 the top by a cap *b* and has at the bottom a

nozzle *b'* in which is formed the valve controlled outlet passage *b*² of the cup.

Forming part of or secured to the nozzle structure *b'* and extending up into the cup *a* is a tube *q*, and to a transverse opening in the lower portion of this tube and corresponding openings in the nozzle structure *b'* is adapted a transversely moving valve *i* notched or slotted for engagement with the lower end of a spring arm *n* which is suitably mounted at the upper end of the tube *q* and extends downwardly through the same for engagement with the valve *i* as illustrated.

The tube *q* serves as a guide for the hollow threaded stem *c'* of a plunger *c*² which fits snugly to the inner wall of the cap *b*, and is acted upon by a coiled spring *r* disposed between the back of the plunger *c*² and the under side of the cap *b* and tending to constantly depress said plunger. The threaded plunger stem *c'* passes freely through an opening in the cap *b* and is provided above said cap with a nut *c* which can be adjusted on said stem so that, by contact with the cap *b*, it will limit, to any desired extent, the depression of the plunger *c*² under the pressure of the spring *r*.

The normal position of the spring arm *n* is that represented in Fig. 5 and tending to move the valve *i* so as to almost close the outlet passage *b*²; this position of the valve corresponding with the fully charged cup in which the plunger *c*² is raised to its highest point and the spring *r* is fully compressed, thus insuring maximum downward pressure upon the plunger to force the lubricant from the cup. As the volume of lubricant decreases, however, and the spring *r* expands, the pressure upon the plunger *c*² gradually diminishes and in order to offset this diminution of pressure the valve *i* should be moved 95 so as to gradually open the discharge passage *b*² in proportion to such diminution of pressure upon the lubricant. This result is effected by mounting upon the upper end of the hollow stem *c'* of the plunger, a regulating pin, or control valve stem *e*, which projects down inside said stem and into the tube *q*, whereby, as the plunger descends, the pin *e* will also be caused to descend and will act upon the inner face of the spring arm *n* so as to move the same from the position shown in Fig. 5 to that shown in Fig. 1 and thereby cause corresponding movement

100

110

of the valve *i* in order to gradually open the discharge passage *b*² to accord with the decreasing pressure upon the lubricant and thus provide for a constant and uniform flow of the lubricant to the bearing which is to be lubricated. The valve *i* is provided with the ports *p* to correspond with the ports *o*, so as to provide a continuous passage for the lubricant from the cup *a* to the outlet passage *b*².

The hollow stem *c'* is provided with a nut *d*, as illustrated, of sufficient dimensions to allow of the threading of the pin *e* therein by means of the orifice *e*², either upwardly, 15 advancing the contact of the pin *e* with the spring arm *n*, or downwardly, retarding the contact of the pin *e* with said spring arm *n*. In my former invention, hereinbefore referred to, the finger 12, corresponding with the pin *e* in the present device, is not susceptible of being regulated, being fixed in its position. By regulating this pin, upwardly or downwardly, as just described, it will permit of the opening of the valve *i* earlier 20 or later as the tension of the spring or the requirements of the bearing may require.

A lug, or extension, *j* is provided on the nozzle member *b'*, in which is positioned, as illustrated, a screw *k*. By the adjustment of this screw *k* the lead of the valve *i* may be limited to a predetermined position, as the progress of said valve is halted as soon as it comes in contact with the said screw *k*.

A locking device, comprising a member *f'* formed with the circular or ring portion *f*, to encircle the hollow stem *c'* has the free end thereof secured to a lug *l* on the body of the cup *a* as illustrated and is pivotally mounted on the cover *b* of said cup *a* by means of the pin *h*, which is engaged with lugs *g* on said cover *b*. A spring *m* is positioned between such cover *b* and the member *f'*.

To remove the cover *b* pressure is exerted 45 on the ring portion *f* of the locking device *f'* disengaging said locking device from engagement with the lug *l*, the cover then being taken off in the usual manner. With this locking device in operative position means 50 are provided to retain the cover *b* in place and prevent the same from backing off.

Various modifications in the construction of my lubricator may be made without departing from the scope of my invention.

Having thus described my invention what 55 I claim as new and desire to secure by Letters Patent is:

1. In combination, a lubricating cup having an outlet, a spring actuated plunger in said cup for forcibly discharging the lubricant through said outlet, a valve controlling the outlet and movable independently of said plunger, means for moving said valve simultaneously with the plunger and means for adjusting and limiting the lead of said 60 valve comprising a valve stem, an extension provided on the outlet structure through which said valve stem extends and being inferiorly threaded to engage the exterior threads of an adjusting screw and an adjusting screw, substantially as shown and described.

2. In combination, a lubricating cup having an outlet in its bottom, a valve mounted for opening and closing movement with respect to said outlet, a spring actuated plunger in the cup, a hollow stem connected with said plunger and having an opening in the top thereof, an adjusting nut on said stem, a tubular member arranged in the stem and 65 supported by the lower portion of the cup, a cam device comprising a spring plate secured to said tubular member at one end and having interlocking connection at its other end with the valve, an actuating member 70 carried by the hollow stem and operating in the tubular member to engage the cam device, comprising a pin threaded into said adjusting nut through the opening in said stem whereby the opening movement of said 75 valve may be advanced and retarded, substantially as shown and described.

3. In combination, a lubricating cup having an outlet, a spring actuated plunger in said cup for forcibly discharging the lubricant through said outlet, a valve controlling the outlet, compression means for moving said valve proportionately with the movement of said plunger and means to limit such movement of the valve to a predetermined 80 position.

In testimony whereof I affix my signature in the presence of two witnesses.

JOHN FRANKLIN MACINDOE.
